CLAIM

The ornamental design for an electronic device case with stethoscope, as shown and described.

DESCRIPTION

FIG. 1 is a front perspective view of an electronic device case with stethoscope showing our new design, without the detachable diaphragm for clarity of disclosure;

FIG. 2 is a front view thereof;

FIG. 3 is a back view thereof;

FIG. 4 is a left side view thereof;

FIG. 5 is a right side view thereof;

FIG. 6 is a top view thereof;

FIG. 7 is a bottom view thereof;

FIG. 8 is an exploded front perspective view thereof, showing the detachable diaphragm separated for clarity of disclosure; and,

FIG. 9 is another front perspective view thereof, showing the detachable diaphragm in an attached state.

The broken lines depict unclaimed portions of the case, acoustic collector, and an unclaimed electronic device that form no part of the claimed design.
